UNITED STATES PATENT OFFICE

THOMAS L. KNIPE, OF KOKOMO, INDIANA

FLORAL DISPLAY STAND

Application filed January 30, 1931. Serial No. 512,435.

My said invention relates to stands designed especially for use in making floral displays, particularly of cut flowers in containers, and the object is to provide such a stand 5 which is not only inexpensive to manufacture and efficient in use but one by which the flowers may be displayed in a variety of forms to suit different tastes or conditions, all as will be hereinafter more fully described and 10 claimed.

Referring to the accompanying drawings, which are made a part hereof and on which similar reference characters indicate similar parts,

15 Figure 1 is a perspective view of one of my improved stands of the preferred form;

Figure 2, a similar view of a modified form;

20 Figure 3, a similar view of another modified form;

Figure 4, a similar view of another modified form;

Figure 5, a similar view of still another form; and

25 Figure 6 a view of one of the baskets or flower container supports for use in connection with and as a part of such stands.

This invention is in general of a similar nature to that forming the subject matter of 30 my application No. 508,507 filed January 13, 1931, but is of different construction in details.

The main part of the stand comprising legs 10, 11, and 12, as shown in Figure 1, is in the 35 main similar to the construction shown in my aforementioned application. A cross-bar 13 connects the legs 10 and 11 near their upper ends and leg 12 is pivotally connected therewith. A triangular brace 14 is pivotally 40 mounted on another cross-bar 15 midway the length of said legs 10 and 11 and has an eye 16 through which leg 12 extends providing a swinging and folding connection as in said aforementioned application. At the upper 45 end of legs 10 and 11 another cross-bar 17 is provided and a handle 18 in the form of a hoop is connected to the legs 10 and 11 at the point of the connection with the cross-bar 13 and also is connected to the outer ends of said 50 bar 17 thus forming a substantial construc-

tion. A series of supports in which the flower containers 19 (indicated by dotted lines in Figures 1 and 4) may be mounted are provided, each of which comprises an upper frame 20 and a lower frame 21 connected by uprights 22, 23, 24, and 25. Said frames 20 and 21 are each oval-shaped being round at their ends and of a length so that when hanging in position for use on the stand they will be in a substantially vertical position, the 55 length being sufficient so that they will rest and be supported against the legs 10 and 11. Uprights 23 and 24 extend above the frame 20 and are formed with hooks 26 and 27 on their upper ends which are adapted to hook 60 over cross-bars 15, 13, and 17 on the stand as shown in Figure 1. A horizontal bar 29 forms the bottom of these supports for the 65 flower containers to rest upon.

These supports just described are adapted 70 to receive and support the flower containers 19 and may be of a length to receive two, three or more containers according to the size of the containers, or the size of the stand.

In Figure 2 I have shown a stand of some- 75 what different form, comprising three legs permanently attached to a frame comprising the members 30 and 31 connected by a cross-bar 32 and having a hoop-shaped handle 33. The supports for the flower containers are 80 hung to the bars of these members in a similar manner as illustrated in Figure 1.

Figure 3 illustrates another form of stand substantially like the stand shown in Figure 1 except that the two main legs are formed 85 of a single piece of wire and are extended at the top to form the handle 35.

The stand illustrated in Figure 4 consists of a single pedestal 36 with a wire base 37 and a flower container support 38 similar to that 90 shown in Figure 2 to which of course additional flower containers may be hung to the upper or lower cross-members, as illustrated in Figure 2.

The stand illustrated in Figure 5 is similar 95 to that in Figure 1 except the top or handle 18 is omitted. It is intended for use where fewer flower containers are employed.

Figure 6 illustrates particularly the structure of each of the baskets or supports which 100

are to be hung to the different parts of the stand for supporting the flower containers.

By the use of such stands and the removable and replaceable flower container supports it will be understood that a great variety of displays may be readily obtained, and such displays as desired or adapted for a large variety of purposes and situations. A stand is also provided that is capable of being packed in small space for shipping or storage purposes.

It will be obvious to those skilled in the art that various changes may be made in my device without departing from the spirit of the invention, and I therefore do not limit myself to what is shown in the drawings and described in the specification but only as indicated in the appended claims.

Having thus fully described my said invention, what I claim as new and desire to secure by Letter Patent, is:

1. A flower display stand comprising inclined legs, cross-bars and receptacle-like supports for flower containers which supports are formed separate from the stand and are provided with hooks for hanging them upon any one of said cross-bars of the stand, said supports being so positioned that their bottom edge will rest against and be supported by said legs and each of said supports being provided with means adapted to be engaged by and to support similar supports for flower containers, substantially as set forth.

2. A device of the kind described comprising the combination with a flower display stand having legs and cross-bars, of a plurality of flower container supports having top and bottom edges, said supports having means adjacent their top edges for detachably securing them in position, some of the supports being secured to said cross-bars and other of said supports adapted to be mounted upon the top edges of adjacent supports whereby said supports may be attached to the stand in different relationships and a variety of displays provided by use of the same stand, substantially as set forth.

In witness whereof, I have hereunto set my hand at Kokomo, Indiana, this 24th day of January, A. D. nineteen hundred and thirty-one.

THOMAS L. KNIPE.
